UNITED STATES PATENT OFFICE.

FRED HARRIS LYNDS, OF NORTH ATTLEBORO, MASSACHUSETTS, ASSIGNOR TO WHITING & DAVIS COMPANY, A CORPORATION OF MASSACHUSETTS.

MESH MACHINE.

Application filed August 27, 1926. Serial No. 131,874.

This invention relates to the manufacture of link-mesh fabric, which is a material widely known in the arts and frequently used for articles of jewelry, such as ladies' hand-bags. More particularly, the invention is concerned with the provision of a machine for making mesh fabric of the kind commonly known as "fish-scale" mesh. Such mesh consists of links of two kinds, and is made up of a multiplicity of rings arranged in rows extending lengthwise and transversely of the fabric, and cruciform connecting links, the legs of which are engaged with pairs of rings of adjacent rows. In such mesh there are as many cruciform links as there are rings, and each ring is engaged by a leg of four different cruciform links.

In the manufacture of fish-scale mesh, as heretofore carried on, machines of several different types have been employed. In some of these machines, supplies of finished rings and cruciform links in the form of flat blanks are provided, the rings and blanks being stored in suitable magazine tubes. Feeding devices are employed which operate to withdraw a ring and a blank from each supply and to deliver the ring and blank to tools which turn the legs of the blank to give it a staple form, and then insert its legs through three of the rings already incorporated in the fabric and through the ring to be added thereto, after which the tools turn the legs inwardly to complete the connection. The rings and blanks which are supplied to this machine are formed in advance, and in accordance with the previous practice, separate machines are used for the purpose. As these link-forming machines require attendants additional to those who operate the mesh machines, their operation involves considerable expense for power and labor, and as the separate formation of the rings and cruciform blanks from the metal stock produces a large amount of scrap, this method of manufacture of the mesh fabric is expensive, and the cost of the finished product is correspondingly high.

In another type of machine which is widely used, the material of which the links are to be made takes the form of flat strips of metal, one of which consists of a series of connect-

ed rings formed from flat stock by punching operations carried on in a stamping machine, while the other strip of stock is in the form of a series of cruciform links, the legs of adjacent links being connected. In the operation of the machine to which such material is supplied, the strips are fed by appropriate devices to tools which sever a ring from the end of the ring strip and a cruciform blank from the end of the other strip in each operation, and the tools then incorporate the ring and the cruciform link in the fabric in the usual way. Here again the material of which the fabric is made must be prepared in advance and as the ring strips and cruciform blank strips are made on separate machines, and in the operation of each machine a large amount of waste is produced, the labor charges for producing the link material and the losses of stock in its production are important items in the cost of the finished product.

The present invention is directed to the provision of a machine by which fish-scale mesh may be made more cheaply than has heretofore been possible, and this machine is arranged and constructed so that it is supplied with stock in the form of a single metal strip of appropriate weight, from which the machine forms both rings and cruciform blanks. These rings and cruciform blanks are cut alternately from the stock and the rings are cut from the small pieces of metal which lie between the legs of adjacent cruciform blanks, such pieces of metal having heretofore been discarded as scrap. The rings and cruciform blanks cut from the strip are delivered by the machine to magazine devices which in turn feed them to the tools by which the two kinds of links are incorporated in the fabric. The fabric is in the form of an endless web or belt mounted on a support and the web and tools are given a step-by-step relative movement. At each step in this movement a ring and a blank are formed and placed in their magazines and the tools withdraw a ring and a cruciform blank from the magazines, insert the legs of the blank through the ring about to be incorporated in the mesh and through three rings already attached to the fabric, and then close the

legs to complete the connection of the new ring. After this operation of the tools, they return to their original position, another step in the relative movement of the tools and the 5 fabric takes place, and the magazine devices are advanced to receive another ring and blank and to bring another ring and another cruciform blank into appropriate position to be acted on by the tools.

10 In the fish-scale mesh which has been made heretofore, the cruciform blanks employed have consisted ordinarily of a flat plate-like portion having four extending legs forming the cross. The flat plate portion of the link is commonly given a high finish in the finished product, and the mesh has a noticeable sheen. For some purposes, however, it is desirable that the flat parts 15 of the cruciform links should not have this glittering surface, and the present machine includes means by which an ornamental fabric may be produced by altering the appearance of the flat surfaces of the cruciform members, as, for example, by an embossing 20 operation. For this purpose, the machine includes suitable tools which act on the stock at points which are to lie within the outlines of the plate-like portions of the cruciform links, and this part of the mechanism 25 is under the control of a pattern device so that plain or ornamental cruciform links may be incorporated in the fabric in any predetermined manner. This pattern control permits the production of a fabric in 30 which there are ornamental links arranged in rows or in bands alternating with rows or bands of plain links; or, if desired, the ornamental links may be incorporated in irregular areas determined by the pattern 35 device.

40 In the embodiment of the invention which is preferred, the narrow strip of metal stock is fed with a step-by-step movement beneath forming tools which punch therefrom round pieces of metal forming the interior of the 45 rings. The stock with the spaced holes in it is then advanced to a second pair of forming devices which punch a narrow strip of metal from the stock around the periphery 50 of each opening so made, this narrow strip constituting a ring. The tools are arranged to remove these rings from the stock and then force the rings back into the openings 55 from which they have been removed, so that the rings are replaced in the plane of the stock and moved with it through the devices which later act on the stock. The cruciform blanks are punched from the portions of the stock which lie between pairs of adjacent 60 rings and the cruciform blanks are first removed from the stock and then replaced in it to lie in its plane. By thus cutting the rings and blanks from the strip and then restoring them to their original positions, 65 the handling of the rings and blanks is

greatly facilitated, the strip affording a convenient means of delivering this link material to the magazines. The strip with the rings and blanks held in place by friction moves directly from the forming devices 70 past the magazines which are spaced apart and associated with these magazines are means by which the rings are successively delivered to one magazine and the cruciform blanks to another. In the insertion of the 75 cruciform blanks in the magazine, the legs of each blank are turned at an angle to their connecting plate member so as to give the blanks a staple form.

80 The magazine devices receiving the rings and cruciform blanks at separated points deliver the rings and blanks to a single point at which are suitable tools past which the edge of the fabric on a support is advanced with a step-by-step movement. At each 85 step in the movement, the tools withdraw a cruciform blank from its magazine, insert three of its legs through rings previously attached to the fabric, and the fourth leg through a ring in the ring magazine. The 90 tools further act to bend the legs inwardly so as to complete the connection, and after such operation, the tools are returned to their original position, the piece of mesh is advanced by a distance corresponding to the 95 diameter of a ring, the magazine devices are moved to receive a new ring and blank and to present another ring and cruciform blank to the tools, and the cycle of operations is repeated.

100 With this machine, it will be apparent that since a single strip of stock is employed and part of the links are made of parts of the stock which it was previously found necessary to discard, the stock is used in the most economical manner and for that reason the cost of production of the finished product is greatly lowered. This cost is further reduced because the machine performs both the mesh-making operation and the operations of producing links of both kinds from the blank stock, whereas in the machines as heretofore constructed, it has been necessary to supply these machines with links of both kinds either in finished or in semi-finished 115 condition and produced on separate machines. Accordingly, the labor charge for the finished mesh is much reduced. Also, the present machine is of compact construction and all its working parts are readily accessible so that inspection and replacement of parts which are likely to become worn is readily carried on without the necessity of putting the machine out of service for any considerable period.

120 For a better understanding of the invention, reference may be had to the accompanying drawings, in which

125 Fig. 1 is a view of the machine in front elevation,

20 Fig. 12 is a plan view of the blank strip showing the sequence of operations which are performed on it,

Fig. 13 is a plan view, partly in section and with parts removed, showing the magazine devices and a part of the mesh support, and

Figs. 14 and 15 are vertical sectional views on the lines 14—14 and 15—15 respectively of Fig. 13.

Referring now to the drawings, the machine is shown as consisting of a bed plate 20 supported on a standard 21, of any convenient type. Resting on the bed plate is a frame member 22 hinged to the bed plate at one edge, as indicated at 23. The frame member 22 carries the operating mechanism of the machine and the member 22 may be swung on the hinge to upright position so that the various parts of the machine are readily accessible.

40 The machine is driven by a pulley 24 mounted on a stud 25 secured to the frame member and fast to a pinion 26 meshing with a gear 27 on the main drive shaft 28 of the machine. This drive shaft is supported in a rear bearing 29 mounted on the standard 30 secured to the frame member 22 and at its front end is journaled in a bearing block 31 secured to the frame member 22. At one end the shaft is provided 45 with a hand wheel 32 by which it may be moved to set the various parts driven by the shaft in proper position for inspection or repair. The gear 27 is loose on the main drive shaft 28 and is provided with part of 50 a clutch, generally designated 33, the cooperating clutch member 34 being operable by a bell crank 35 pivoted in a bracket 36 and operated by a rod 37 with a handle 38 at the front of the machine. By disconnecting the clutch, the machine may be stopped.

The main drive shaft is provided with a spiral gear 39 meshing with a similar gear on a countershaft 40 journaled in bearings 41 at either end of the bed plate 22. The 55 main shaft and the countershaft carry a

plurality of cams which, by means of levers, positively operate the working parts of the machine.

The stock of which the links are to be made is in the form of a strip 42 drawn 70 from a supply (not shown) by means of upper and lower feed rolls 43, 44. The lower roll has a spindle journaled in bearing blocks 45 in standards 46 projecting upwardly from the bed of the machine, and the upper roll has a spindle journaled in movable bearing blocks 47 lying in slots in the standards 46. Springs 48 are placed between the upper bearing blocks and the cover plates 49 closing the upper end of the 75 slots in standards 46, these springs forcing the blocks downwardly and causing the feed rolls 43 and 44 to bear against each other with a yielding pressure. On the spindle of the lower roll 44 is a ratchet 50 engaged by a pawl 51 mounted in an arm 52 secured to the end of a rock shaft 53 mounted in standards 54. Secured to the other end of the rock shaft is an arm 55 carrying a roll 56 entering a peripheral channel 57 in a cam 80 disc 58 mounted on the countershaft 40. The shape of this channel is such that at each revolution of the countershaft the pawl 51 is swung to advance the ratchet 50 by one tooth. A pin 59 on the arm 52 carries a 85 leaf spring 60 bearing against the upper face of the pawl and serving to hold it in contact with the teeth of the ratchet. Both rolls are positively fed by the pawl and ratchet by means of a gear 61 mounted on the forward end of the spindle of the lower roll and meshing with a similar gear on the spindle of the upper roll 43.

As the countershaft rotates, the strip which is yieldingly gripped between the feed 95 rolls, is advanced by means of the pawl and ratchet with a step-by-step movement. At the completion of each step, various operations are successively performed on the strip. The successive performance of these operations requires that the strip be accurately centered and a special centering device, later to be described, must be employed for the purpose, since the feeding rolls, due to play 100 in the gears and wear, cannot be depended on. In order that the centering device may 105 perform its function, the feed rolls must be moved to release the strip as the centering action takes place and for this purpose the following mechanism is used.

110 Mounted on a pin 62 in the standards 46 is a yoke 63 (Figs. 1 and 2), this yoke having a bifurcated end, the legs 64 of which extend between the spaced standards 46 and lie beneath the spindle of the upper feed roll 43. At its rear end the yoke terminates in a tongue which lies beneath an arm 65 carrying an adjustment screw 66 which bears on the tongue. The arm 65 is mounted on a rock shaft 67 suitably supported in the 115 120 125 130

bearing block 31 and at its rear end carries an arm 68 provided with a roll 69 bearing against the face of a disc 70 mounted on the main shaft. This disc has a projection 71 which contacts with the roll 60 and thus rocks the shaft 67, swinging the yoke 63 on its pivot and raising the upper feed roll clear of the lower one. This releases the blank so that when the centering device performs its function the blank may be moved lengthwise whatever amount may be necessary in order to center it properly.

As the blank is advanced by the feed rolls, it first passes between tools by which an ornamental character is given to the flat plate-like surfaces of the cruciform links. In the machine as illustrated, this flat surface is provided with a projection or knob 72 (Fig. 12) and this knob is formed by co-acting die members 73 and 74. The upper die member 73 takes the form of an anvil mounted in a block 75 secured by means of brackets 75^a to the end of a slide 76 movable in dove-tail guide-ways 77 in the bearing block 31. This die member has a shank 78 entering an aperture in the block 75 and its position is adjusted by means of an adjusting screw 79 threaded into the upper end of the aperture. The lower die member 74 comprises a shank 80 and a pin 81, the shank being disposed in a bore in a block 82 mounted on the frame of the machine. The block 82 has cover plates 83 and 84 having openings through which the pin and shank respectively project. At its lower end, the shank rests on a pin 85 (Fig. 8) this pin lying in a part of the frame member. Beneath the pin 85 and lying in a bore in the frame member, is a plunger 86 having a reduced end 87 connected to the main part of the pin by an inclined shoulder 88. A leaf spring 89 mounted rigidly at one end, has its free end received in a slot in the plunger 86 and pivotally mounted on the frame member is a bell crank 90, one arm 91 of which enters a slot in the plunger. The other arm 92 of the bell crank forms an armature for an electromagnet 93 of any suitable construction, and when the armature is energized, the bell crank is rocked on its pivot, forcing the plunger into its recess. The pin 85 rides up the inclined shoulder 88 and raises the die member 80 against a spring 94 which lies in a recess in the block 80 and surrounds the pin 74. At the time the solenoid is energized, the anvil member 73 is lowered against the strip 42 and the pin 74 upsets the metal into a depression 95 formed in the end of the anvil member, thus producing the projection 72. The operation of the solenoid is under the control of a pattern mechanism presently to be described. That portion of the strip being acted on by the die members 55 and the next adjacent cutting mechanism

which removes the central portions of the rings from the strip is guided past these devices by guide plates 96 secured to the top of the plate 83 and partially overlying the strip.

The block 75 carries a cutting plunger 97 in alignment with the dies 73 and 74. This plunger is disposed within a bushing 98 and carries an enlargement 99 at its upper end which lies in an enlarged recess in the bushing, being secured adjustably in position by means of a set screw 100. A plug 101 is threaded into the recess in the upper end of the bushing and bears against the upper end of the cutting plunger to act as an abutment therefor. The block 75 is mounted in position on the end of the slide 76 in such manner that the lower end of the slide closes the upper end of the bushing and holds it securely in position. The projecting end of the plunger 97 cooperates with a shearing recess 102 in the form of a bushing in the plate 83 and as the slide 76 descends, the plunger shears a circular piece of metal from the strip, as indicated at 103, forcing this removed portion into a passage 104 through block 82 and plate 84, whence the piece leaves the machine. The disc 103 is the exact size of the center of each ring which is to be incorporated in the mesh.

Passing beyond the cutting plunger, the strip moves beneath a centering punch 105 which takes the form of a pin having an enlarged shank and a rounded end, the shank being received in a recess in the block 75. A bore 106 is formed in the plate 83 directly beneath the pin 105 and the spacing between the centering punch and the cutting punch 97 is substantially equal to the distance that the strip is advanced at each step. As the block descends, the centering punch 105 passes through one of the openings formed by the punch 97 and at the time the pin enters the recess 106 the feed rolls have been freed from the strip so that if the strip is not properly aligned so that the later operations may be performed on it, the centering punch will advance or retract the strip by the correct amount.

Beyond the centering punch is the device 115 for cutting the rings from the strip, and this device acts to remove from the strip the piece of metal constituting the ring and then to replace this ring in the plane of the strip. This device comprises upper and lower die members 107 and 108. The upper die member is in the form of a pin having an enlarged shank 109 and it is mounted in a bushing 110 carried in a recess in the block 75. Above the enlarged end 109 of the die member is a block of rubber 111 and a plug 112 is threaded into the recess and serves as a stop against the upper end of the rubber block. At the lower end, the bushing 110 has a conical surface 113 with the die 130

member 107 projecting slightly from the bushing at the apex of the cone.

The lower die member comprises a pin 108 with an enlarged shank 114 received in the recess in the block 82, the position of the die member being adjustable by means of an adjustment screw 115 threaded into the plate 84. A movable sleeve 116 is slidably mounted on the pin 108 and a spring 117 bears against the shank 114 and the lower end of the sleeve. The sleeve projects into an opening in the plate 83 and normally lies flush with the upper end of the pin 108 bearing against the under surface of the strip.

In the operation of the die members, as the slide 76 descends, the upper die member 107, the diameter of which is the same as the lower die member 108, bears against the edge of the strip around the opening formed by the removal of the piece 103 and further movement of the slide 76 causes this upper die member to compress the block of rubber, while the bushing 110 moves beyond the end of the member 107. In such movement the edge of the conical surface 113 at the opening through which the die member 107 projects, contacts with the upper face of the sleeve 116 and shears from the strip the ring held between the members 107 and 108. In such shearing action the strip is forced downwardly slightly by the bushing 110 pressing against sleeve 116 and causing compression of the spring 117. As the slide 76 then rises, the bushing 110 moves away from the face of the sleeve 116 and the spring 117 restores the bushing to its original position. During this action the ring sheared from the strip is held tightly between die members 107 and 108, the block of rubber 111 expanding to insure that the ring will be tightly gripped between these members. When the die member 107 is finally removed from the face of the ring, the latter lies within the opening formed in the strip by its removal and as the strip is advanced, the ring is moved with it.

Passing beyond the device which cuts the ring from the strip and then restores it to position, the strip enters the device cutting the cruciform links, and this device is of a construction somewhat similar to the device for cutting the rings. It consists of a plunger 118 of cruciform section formed with an enlarged shank 119. The plunger 118 is disposed in a suitable recess in a bushing 120 in a recess in block 75, the bushing being held in position by a set screw 121. A block of rubber 122 is disposed in the recess above the upper end of the shank 119 and a block 123 is threaded into the upper end of the recess to serve as an abutment for the rubber block. The lower member comprises a cruciform rod 124 having an enlarged shank 125 disposed in a recess in the block

82, an adjustment screw 126 providing for the exact adjustment of the rod in the block. A set screw 127 permits the rod to be anchored in position when once adjusted. Within the recess in the block 82 above the shank 125 is a movable sleeve 128 through which the rod 124 passes. A block of rubber 129 lies between the upper end of the shank 125 and the lower end of the sleeve. The lower end of the plunger 118 has a recess 130 to receive the projection 72 formed in the strip and to lie at the center of each plate member of the cruciform links.

In the operation of the parts, the descent of the slide 76 causes the part of the strip which is to form the cruciform link to be gripped between the end of the plunger 118 and the end of the rod 124, and as the slide further descends, the edge of the conical surface 131 at the end of the bushing 120 bears against the strip along the outlines of the cruciform link and shears the metal by coaction with the rod 124. The cruciform link is wholly freed from the strip, being held between the fixed rod 124 and the yielding plunger 118, the stock around the cruciform link being moved clear of the link by the compression of the block 129, resulting from the pressure of the bushing 120 against the sleeve 128. When the slide rises, the stock is restored to its original position and the cruciform link replaced in the aperture in the stock from which it was removed.

The block 75 secured by brackets 75^a to the lower end of the slide 76 is readily removable when occasion arises and the mounting of the various tools in this block is such that the tools can be quickly removed and replaced if necessary. Similarly, the block 82 may be removed from the frame member without difficulty, and the plate 84, which is of dove-tailed form (Fig. 8) may be slipped from its channel in the block 82 so that the die members in this block may be quickly removed and replaced.

The movement of the slide 76 to raise and lower the block 75 is brought about by means of a link 132 eccentrically mounted on the end of the main drive shaft 28, the upper end of the link being mounted on a pivot 133 in an adjustment slide 134 provided with a threaded shank 135. This shank is inserted in the slide 76 and threaded through an adjustment nut 136 lying in an aperture in the slide. By turning this nut the slide 134 may be raised and lowered with reference to the slide 76, thus adjusting the length of the reciprocation of the slide 76. At the upper end, the shank 135 carries a lock nut 137. The slide 76 has an aperture 138 to permit the swinging of the eccentric link 132.

The strip with its alternate rings and cruciform members severed from it by lying in its plane, advances past the forming devices to the magazine devices. In such move-

ment the strip enters a channel in a plate 139 and beneath this plate is mounted a dial 140 (Fig. 13). This dial has semi-circular recesses 141 in its periphery, and is carried 5 on the upper end of a disc 142 mounted on a shaft 143 extending through a portion of the frame of the machine. At its lower end the shaft carries a ratchet 144 engaged by a pawl 145 mounted on a slide 146 (Fig. 5). 10 The slide 146 has an opening with inclined shoulders 147 through which passes a slide 148 which has similar inclined shoulders 149 at one side of the opening. This slide 148 is 15 suitably mounted in the block 22^a and at one end has upstanding lugs 150 between which lies a knob 151 on the end of a lever 152 mounted on a rock shaft 153 supported on suitable standards 154 extending upwardly from the bed of the machine. The shaft 20 carries an arm 155 at its rear end provided with a roller 156 bearing against the face of the disc 157 on the countershaft, this disc having a projection 158 which, as the disc rotates, causes the shaft 153 to be rocked and 25 thus causes the slide 148 to be reciprocated in the direction of its length. A spring 159 secured to the slide and to a fixed part of the machine tends to move the slide to hold the roller 156 against the face of the disc 157. 30 Each time the slide is moved to the right (Fig. 5), its inclined shoulders 149 cause the slide 146 to be moved so as to cause the pawl 145 to move behind a tooth on the ratchet 144, and the opposite movement of 35 the slide 146 causes the ratchet to be moved by one step, thus advancing the dial plate.

The periphery of the dial lies beneath the strip of stock and in each movement of the plate and strip, one of the recesses 141 is in 40 position to receive a ring from the strip. For this purpose, there is provided a plunger 160 mounted in a recess in block 161, secured to the block 31. This plunger has an enlarged shank 162 lying in contact with a 45 rock shaft 163 having a flattened portion 164. A spring 165 holds the shank in contact with the rock shaft. This shaft, which is journaled in the block 161, carries an arm 166 provided with a roller 167 (Fig. 2) bearing 50 against a cam disc 168 on the main shaft, and as the shaft rotates, the cam disc causes the rock shaft 163 to be rocked and this causes the plunger 160 to be raised and lowered. In its downward movement, the tip of 55 the plunger bears against one of the rings in the strip of stock 42 and forces this ring into a recess 141 in the dial plate. As the dial plate advances, it carries the ring with it, the ring being held in position between the 60 plate and a shoulder 169 formed on a plate 170 which surrounds the dial plate. The rings 171 are advanced by the dial plate to the tools by which they are incorporated in the mesh. The rings being carried through 65 an arc of 90° by the dial plate.

The strip from which the rings have been removed but which still carries the cruciform links, advances past the plunger 160 beneath a magazine block 172. This block is mounted on the end of a shaft 173 carried 70 in the block 161 and the magazine block 172 has a plurality of circular bores formed in it, these bores coming into position as the magazine is rotated, directly above the strip and in the position such that cruciform 75 links may be forced into them. In such introduction of the links into the bores, the legs of the links are bent at right angles to the plane of the plate to which they are attached, the cruciform blanks thus being 80 given the staple form.

For the purpose of removing the cruciform blanks from the strip and forcing them into the apertures in the magazine block, there is provided a vertical slide 174 having an offset 85 extension 175 at its lower end carrying an upright pin 176. The slide 174 is mounted in a channel in the block 177 secured to the block 31 and entering an aperture in the slide is the end of an arm 178 mounted 90 on a rock shaft 179 (Fig. 2) journaled in the block 31, the rock shaft also carrying an arm 180 provided with a roller 181 bearing against a cam disc 182 on the main drive shaft. As the drive shaft rotates, the shaft 179 is rocked to raise and lower it, and in each upward movement of the slide 174 the pin 176 bears against the central portion of 95 a cruciform blank carried in the strip stock and forces this blank into a recess in the magazine block 172. In such action the legs of the cruciform blank are bent at an angle to the plate portion to give the blank the 100 staple shape shown at 183 (Fig. 14). After the link has been forced into the magazine 105 block the latter is raised, then rotated a step to bring the next aperture into alignment with the next blank in the strip, then lowered to position, and the slide 174 again rises to introduce the link blank into the 110 aperture in the block.

The upward and downward movements of the magazine are brought about by a yoke 184 pivoted at 185 on the upper end of the block 31, the yoke carrying rollers 186 on either leg which lie between collars 187 fast on a rod 188 formed as an extension of the shaft 173 on the lower end of which the magazine block 172 is mounted. The yoke at its other end carries a roller 189 bearing against a cam disc 190 on the countershaft, and at each rotation of the countershaft, the yoke raises and lowers the magazine block 115 in the manner described. The rotation of the block is brought about by means of 120 a recessed wheel 191 fast on the shaft 173, one of the recesses in this wheel receiving a pin 194 on the end of a slide 195 when the shaft is raised by the yoke. The slide 195 is carried in guides 196 on the side of the 125

block 31 and at its rear end has upwardly extending arms 197 (Fig. 3) between which lies the knobbed end of a lever 198 pivotally mounted at 199 on a bracket 200 secured to the upper surface of the block 31. The lever 198 carries a roller 201 lying in a channel in a cam disc 202 on the main shaft. The shape of this channel is such that at each rotation of the main shaft the slide is reciprocated. As the shaft 173 is raised by the yoke, one of the recesses in the wheel 191 receives the pin 194 on the slide. The slide is then moved rearwardly (Fig. 3) causing the shaft 173 to be advanced a part of a rotation. As the shaft is now lowered by the yoke, a pin 203 fast on the upper end of the block 161 enters one of the recesses in the wheel 191 and holds the shaft against movement.

The addition of links of both kinds to the piece of mesh is carried on by upper and lower co-acting plungers, the upper plunger forcing a cruciform link from the magazine and causing two of its legs to pass through rings of one row at the edge of the piece of mesh, its third leg to pass through a ring of another row at the edge of the piece of mesh, and its fourth leg to enter a ring held in the edge of the dial plate. The lower co-acting plunger then operates to force these legs inwardly so that the cruciform link secures the four rings together.

The upper of the co-acting tools by which the links are incorporated in the mesh is in the form of a plunger 204 carried on a slide 205 mounted in the block 161, this slide having projecting ears 206 between which lies the knobbed end of a lever 207 (Fig. 1) mounted on the rock shaft 163. The slide 205 is positioned above the outer edge of the magazine block 172 at a point approximately 180° beyond the point where the cruciform blanks were forced into it. The rocking of the shaft 163 causes the plunger to be raised and lowered and in its downward movement the plunger enters a recess in the magazine block and forces the cruciform staple out of the block.

The piece of mesh to which links are added is shown at 207 (Fig. 13) extending partly around the horizontal roller 208 in the form of an endless belt 209. The roller has square recesses 210 cut in its face near one end, each of these recesses receiving the legs of cruciform links in the mesh and anchoring the mesh against movement. The mesh is held in place by means of a leaf spring 210^a pivotally mounted at one end in a lug secured to a block 210^b adjustably mounted on the frame member 31, the free end of the spring pressing resiliently against the mesh. Block 210^b has a guiding recess through which the strip passes, the adjustment permitting exact control of the strip. The rings 211 at the edge of the mesh partially overlie the end 212 of the support, which in-

cludes a hollow cylinder 213, resting loosely at one end in a channel 214 in a disc 215 mounted rigidly on a rod 216 supported at one end in a bracket 217 secured to an extension 218 from the machine frame. At its other end, the rod 216 terminates in a disc 219 which is secured to the frame member by bolts 220 (Fig. 10) and supports the inner end of the cylinder. Between the disc 219 and the frame member of the machine is a plate 221 in a slot in which lies the lower forming tool 222. This tool has a shank with a transverse slot with inclined shoulders 223 (Fig. 3) and the end of a slide 224 having inclined shoulders co-acting with the shoulders 223, enters the slot. This slide runs in a channel in a guide plate 225 and at its rear end has a notch 226 in which enters the knobbed end of a lever 227 pivoted at 228 and carrying a roller 229 at its upper end bearing against a cam disc 230 on the countershaft 40. As the countershaft rotates, the slide 224 is reciprocated lengthwise and at each reciprocation it raises and lowers the tool 222. The working end of the tool has a depression 231 in its end for a purpose presently to be described.

The support 208 is given a step-by-step movement of advance by means of a pawl 232 mounted on a slide 233 and held in position by a spring 234. The slide 233 is connected by an adjustment screw 235 to a slide 236, both slides being movable in channels in the plate 225. The slide 236 has an opening having inclined shoulders 237 (Fig. 5) through which extends the end of the slide 148 also having inclined shoulders adapted to cooperate with the shoulders 237. As the slide 148 is reciprocated endwise by the mechanism previously described, it moves slides 236 and 233 endwise, causing the pawl 232 to ride over one of the square recesses formed in the cylinder 213. In the opposite movement of the slide, the support is advanced by the width of such a recess.

In order to adjust the support 208 so that the marginal rings in the belt of mesh are properly positioned with reference to the tools, there is provided an adjusting screw 208^a (Fig. 13) having an inclined end which bears against a similar inclined portion of a pin 208^b. Pin 208^b has a rounded end which bears against one end of the roll 208. At the opposite end of the roll the bracket 217 carries a spring-pressed pin 217' disposed in a recess in the bracket and bearing against the end of the roll 208. By adjusting the screw 208^a the position of the pin 208^b is determined and this in turn determines the position of the roll 208, the latter being held against the end of pin 208^b by the spring-pressed pin 217'.

As the band mesh mounted on the support is moved by the support between the tools, when the mesh has come to rest, the

upper and lower tools move toward each other. The upper tool forces a cruciform staple from the magazine 172 and inserts two of its legs through adjacent links in one 5 row at the edge of the piece of mesh, the third leg through a ring previously added to the mesh, and the fourth leg through a ring carried in the dial 140. These legs projecting through the rings enter the depression 10 231 in the lower tool and as the tools approach, the legs are bent inwardly as shown at 238, thus connecting the ring to three rings previously secured to the mesh by a cruciform link. The tools are now separated 15 by their actuating devices, the support is advanced by a step, and the cycle of operations is repeated.

It will be noted that the links of both kinds are added in rows at the edge of the mesh, 20 these rows extending lengthwise of the mesh. The web of mesh is endless and it is properly placed on the support so that the row of rings to which new links of both kinds are to be added lies at the edge of the support adjacent the tools. As the operation 25 of the machine continues, the web becomes wider and wider, and when a piece of mesh of the desired width is produced, the machine is stopped and the mesh removed.

30 In order that the plate-like portions of the cruciform links may be stamped or embossed with the ornamentation, in accordance with the selected pattern, a pattern mechanism is employed which includes a rotary support 239 mounted on a stud 240 secured to the frame member 22. On this stud is a bell crank 241, to which is secured a pawl 242 placed to engage a ratchet 243 secured to the support by means of the leaf spring 244. A 35 link 245 is connected to one arm of the bell crank lever and at its other end is connected to an eccentric pin 246 on the end of the countershaft. The rotation of the shaft causes the bell crank to be rocked and at 40 each movement the rotary support 239 is advanced by a step. Mounted on the support is an endless pattern sheet 247 (Figs. 3, 9) which may conveniently take the form of a strip of fish-scale mesh, the support having 45 recesses 248 in which the legs of the cruciform links are received. Certain of the cruciform links of this pattern strip have projections 249 and the strip passes beneath a leaf contact member 250, above which is a 50 similar contact member 251. Whenever a 55 knob 249 engages the contact member 250, it raises this member into contact with the member 251, thus completing an electrical circuit which energizes the electromagnet 93, 60 causing the plunger 80 to rise and punch the strip in cooperation with the upper plunger 73. When a cruciform link, such as 252, having a plain surface passes beneath contact members 250 and 251, they remain 65 separated, the electro-magnet is not ener-

gized, and when the upper forming tool 73 descends it does not change the character of the strip 42, since the lower plunger remains in its downward position. By suitably forming the pattern strip, the ornamented 70 cruciform links may be incorporated in the mesh in accordance with any desired pattern, and by the proper choice of forming tools, various operations other than the formation of knobs may be performed on the stock. 75

In Fig. 7 there is shown a mechanism by which the movement of the ring dial may be exactly adjusted. The slide 146 which is reciprocated by the slide 148, consists of a part 146^a engaging the slide 148 and an end 80 member 146^b carrying the pawl 145 and connected to the member 146^b by an adjustment screw 253. This construction permits the path of travel of the pawl to be exactly regulated, thus permitting exact adjustment of 85 the movement of the ring dial from which the rings are extracted by the operation of the incorporating tools.

In the event that the stock 42 being moved past the forming devices becomes jammed, 90 due to variation in the thickness of the stock, or for any other reason, the continued operation of the feeding devices would cause the strip to buckle. If this should occur, the machine is brought to an immediate stop 95 by means of a lever 254 pivotally mounted at a convenient part of the machine and having an extension 255 which is held against the surface of the stock by a light spring 256 connected to the lever 254. At 100 its rear end the lever has a latch 257 engaging a lug on a bell crank 258, one arm of the bell crank carrying a roller 259 bearing against the periphery of the cam disc 157. This disc 157 has a recess 260 formed in it, 105 and a spring 261 tends to rock the bell crank to force the roller 259 into contact with the periphery of the disc 157. The engagement of the bell cranks 254 and 258 normally prevents such movement, but if the strip becomes jammed and commences to buckle, it will rock the lever 254 on its pivot and free the lever 258. The spring 261 will tend to swing this lever on its pivot, but such movement is prevented until the roller 259 is in 110 alignment with the recess 260. When this occurs, the lever 258 rocks and its lower end 262, engaging a shoulder 263 on the rod 37, moves the rod to the rear, thus throwing out of engagement the clutch members by which the main shaft is connected to the drive. The automatic action of this clutch release is possible only when the roller 259 enters the recess 260, and this recess is so placed on 115 the cam disc that the clutch can be automatically thrown out to stop the machine only when the various co-acting parts of the forming mechanism and the link-incorporating tools are separated. This permits the attendant to remove the jam without the 120 125 130

necessity of having to turn the machine over by means of the hand wheel.

It will be seen that the present machine is of compact construction and by reason of the mounting of the various parts in members which are readily removed, and by mounting the upper frame member of the machine on hinges, inspection of the working parts and their replacement is a simple operation. The machine effects a large saving in the final cost of the mesh, since it performs the operations of forming the two kinds of link material from a single piece of stock and of incorporating these links in the piece of fabric. Thus the cost of a stamping machine and the labor and other charges for operating it are eliminated, and, in addition, the present machine effects a further saving of material because the rings are made of portions of the stock which have heretofore been discarded.

I claim:

1. A machine for the manufacture of link-mesh fabric, which comprises the combination of a support for a piece of mesh, tools for incorporating links in the piece of mesh, means for forming links from blank material and delivering these links to the tools, and power-driven mechanism for giving the tools and the piece of mesh a relative movement to present successive portions of the mesh to the tools and for operating the tools and the link-forming means.

2. A machine for the manufacture of link-mesh fabric, which comprises the combination of a support for a piece of mesh, tools for incorporating links in the piece of mesh, means for forming links from blank material and delivering these links to the tools, and power-driven mechanism for giving the tools and the piece of mesh a step-by-step relative movement to present successive portions of the piece of mesh to the tools and for operating the tools in the periods of rest of the step-by-step movement.

3. A machine for the manufacture of link-mesh fabric, which comprises the combination of a support for a web of mesh, tools for incorporating links in the web of mesh along the side edge thereof, means for forming links from blank material and delivering these links to the tools, and power-driven mechanism for giving the tools and the web of mesh a relative movement to present successive portions of the mesh to the tools and for operating the tools and the link-forming means.

4. The combination of a support for an endless web of mesh, tools for incorporating links in the web of mesh in rows extending lengthwise thereof, means for forming links from blank material and delivering these links to the tools, and means for giving the tools and the web of mesh a relative movement to present successive portions of the

mesh to the tools and for operating the tools and the link-forming means.

5. A machine for the manufacture of link mesh fabric made up of links of two kinds, which comprises the combination of a support for a piece of mesh, tools for incorporating links of both kinds in the piece of mesh, means for forming links of both kinds from blank material and delivering these links to the tools, and power driven mechanism for giving the tools and the piece of mesh a relative movement to present successive portions of the mesh to the tools and for operating the tools and the link-forming means.

6. The combination of a support for a piece of mesh, tools for incorporating links of two different kinds in the piece of mesh, means for forming links of both kinds from a single strip of blank material and delivering these links to the tools, and power driven mechanism for moving the tools and the piece of mesh relatively to present successive portions of the mesh to the tools and for operating the tools and the link-forming means in correspondence with the progress of the mesh-making operation.

7. The combination of a support for a piece of mesh made up of links of two different kinds, tools for incorporating links of both kinds in the piece of mesh, means for forming links of both kinds alternately from a single strip of blank material and delivering these links to the tools, and power driven mechanism for moving the tools and the piece of mesh relative to present successive portions of the mesh to the tools and for operating the tools and the link forming means.

8. The combination of tools for incorporating links in a piece of mesh, means for forming links from blank material, means for placing the formed links in a magazine, means for moving the magazine to supply links to the tools, and power driven means for operating the tools and the link-forming means.

9. The combination of tools for incorporating links in a piece of mesh, means for forming links from a strip of blank material and placing these links in a magazine, means for moving the magazine to deliver links to the tools, and operating means for the tools to cause them to withdraw links successively from the magazine and to incorporate these links in the fabric.

10. The combination of tools for incorporating links in a piece of mesh, means for forming links from blank material and placing these links successively in a dial, means for rotating the dial to deliver the links therein successively to the tools, and means for operating the tools to withdraw links successively from the dial and incorporate these links in the piece of mesh.

11. The combination of separate means for forming links of two kinds from blank material and placing these links in separate magazines, tools operating intermittently and at each operation incorporating a link of each kind in a piece of mesh, and means for moving the magazines to deliver a link of each kind simultaneously to the tools. 15
12. The combination of means for forming links of two different kinds from a single strip of blank material and for placing these links in separate magazines, tools for simultaneously adding a link of each kind to a piece of mesh, means for moving the magazines to deliver links to the tools, and means for operating the tools to withdraw a link from each magazine simultaneously and incorporate these links in the fabric. 20
13. The combination of means for removing links from a strip of blank material and restoring these links to position in the strip, a magazine, means for advancing the strip to the magazine and for removing the links and placing them successively in the magazine, means for moving the magazine to deliver the links to a point spaced from the point at which the magazine received the links, and tools at the delivery point operating to withdraw the links successively from the magazine and incorporate these links in a piece of mesh fabric. 25
14. The combination of means for removing links of two kinds from a strip of blank material and for restoring these links to the strip, separate magazines for links of each kind, means for advancing the strip to the magazines and for removing the links of both kinds and placing them in their appropriate magazines, tools operable to withdraw a link of each kind from its magazine and incorporate these links in a piece of mesh fabric, and means for advancing the magazines to deliver links successively to the tools. 30
15. The combination of means for removing links of two different kinds alternately from a strip of blank material and restoring these links to their original positions in the strip, a magazine for links of each kind, means for delivering the links from the strip to their appropriate magazines, tools operable to withdraw a link of each kind from its magazine and to incorporate these links in a piece of mesh fabric, and means for advancing the magazines to deliver links successively to the tools. 35
16. The combination of means for forming links from blank material and placing these links in a magazine, tools spaced from the forming means, means for moving the magazine through a curved path to deliver links successively to the tools, and means for operating the tools to remove links successively from the magazine and to incorporate these links in a piece of fabric. 40
17. The combination of means for forming links from a piece of blank material and placing these links in a rotary magazine at one point in its path of rotation, means for rotating the magazine, tools disposed at a point in the path of rotation of the magazine spaced from the point at which the links were placed therein, and means for operating the tools to remove links successively from the magazine and to incorporate these links in a piece of fabric. 45
18. The combination of forming devices for producing links of two kinds from blank material and for delivering the links of each kind to separate magazines disposed at a distance from each other, means for moving the magazines to deliver links of each kind to the same point, and tools at this point for receiving the links and incorporating them in a mesh fabric. 50
19. The combination of means for moving a strip of blank material lengthwise, forming devices at spaced points in the path of travel of the strip for forming links of two kinds therefrom, separate magazines for receiving links of each kind, means for moving the magazines to bring links of each kind to a common point, and tools at this point for incorporating these links in a piece of mesh fabric. 55
20. The combination of means for moving a strip of blank material lengthwise, forming devices in the path of travel of the strip for forming links of two kinds therefrom, means for delivering the two kinds of links to separate magazines, means for moving the magazines to bring the links carried thereby successively to a common point, and tools at this point for incorporating the links in a piece of mesh. 60
21. The combination of means for moving a strip of blank material lengthwise, means for removing links of two kinds from the strip at different points and for restoring these links to the strip, means at spaced points in the path of travel of the strip beyond the forming means for removing the links from the strip and delivering a link of each kind simultaneously to a single point, and tools at this point for receiving the links and incorporating them in a piece of link mesh fabric. 65
22. The combination of means for moving a strip of blank material lengthwise, forming devices in the path of travel of the strip for forming links of two kinds from alternate portions of the strip, means in the path of travel of the strip beyond the forming devices for removing the individual links of each kind from the strip and for delivering these links to a single point, and tools at this point for successively incorporating a link of each kind simultaneously in a piece of fabric. 70
23. In a machine for making link mesh 75

5 fabric, the combination of means for forming links from a strip of blank material, means for altering the appearance of the parts of the links which are to be exposed in the finished fabric, a delivery device for receiving the formed links and delivering them to a point remote from the forming and altering means, and tools at the said point for incorporating the links in a piece 10 of mesh fabric.

15 24. In a machine for making link mesh fabric, the combination of means for forming links from a piece of blank material, means for altering the appearance of the portions of the links which are to be exposed when the links are incorporated in the fabric, a delivery device for receiving the formed links and delivering them to a point remote from the forming means, tools 20 for incorporating the delivered links in a piece of mesh fabric, and pattern mechanism for controlling the action of the altering means.

25 25. In a machine for making link mesh fabric, the combination of means for forming links from a piece of blank material, means for altering the appearance of the portions of the links which are to be exposed when the links are incorporated in the fabric, a delivery device for receiving the formed links and delivering them to a point remote from the forming means, tools for incorporating the delivered links in a piece 30 of mesh fabric, means for operating the altering means, and a pattern mechanism for controlling the action of the operating means.

40 26. In a machine for making link mesh fabric, the combination of means for forming links from a piece of blank material, means for altering the appearance of the portions of the links which are to be exposed when the links are incorporated in the fabric, a delivery device for receiving the formed links and delivering them to a point remote from the forming means, tools for incorporating the delivered links in a piece 45 of mesh fabric, means for operating the altering means, a pattern member having control areas thereon for controlling the 50 action of the said operating means.

55 27. In a machine for making link mesh fabric, the combination of means for forming links from a piece of blank material, means for altering the appearance of the portions of the links which are to be exposed when the links are incorporated in the fabric, a delivery device for receiving the formed links and delivering them to a point 60 remote from the forming means, tools for incorporating the delivered links in a piece of mesh fabric, electromagnetic means for actuating the altering means, and a pattern mechanism for controlling the said electromagnetic means.

70 28. In a machine for making link mesh fabric, the combination of means for forming links from a strip of blank material, means for embossing the portions of the links which are to be exposed when the links are incorporated in the fabric, a delivery device for receiving the formed links and delivering them to a point remote from the forming means, and tools at the said point for incorporating the links in a piece 75 of mesh fabric.

80 29. In a machine for making link mesh fabric made up of links of two different kinds, the combination of means for forming both kinds of links from a single strip of blank material, means for altering the appearance of the parts of links of one kind which are to be exposed when the links are incorporated in the fabric, separate means for receiving the links of each kind and for 85 delivering a link of each kind simultaneously to a point remote from the forming means, and tools at the said point for incorporating the links in a piece of mesh fabric.

90 30. In a machine for making link mesh fabric, the combination of a support for a piece of mesh, tools for incorporating links in the piece of mesh on the support, a pair of magazines containing links and arranged to deliver these links to the tools, and means 95 for actuating the tools to remove links from the magazines and to incorporate them in the piece of mesh.

100 31. In a machine for making link mesh fabric, the combination of a support for a piece of mesh, a pair of magazines containing links, means for moving the magazines to deliver the links to a common point, and tools at this point for simultaneously withdrawing a link of each kind from the magazines and incorporating these links in a piece 105 of mesh fabric.

110 32. In a machine for making link mesh fabric, the combination of a pair of movable magazines containing links, the magazines being arranged so that there is a common point in the path of movement thereof, tools at the common point, and means for operating the tools to incorporate a link from each magazine simultaneously in a piece 115 of mesh fabric.

120 33. The combination of a pair of movable magazines lying in parallel planes in partially overlapping relation, these magazines containing links, means for moving the magazines, tools disposed at a common point in the path of movement of the magazines, and means for actuating the tools to remove a link from each magazine and to incorporate these links in a piece of mesh fabric.

125 34. The combination of a magazine having a series of recesses along one edge for holding individual links, a second magazine having a series of apertures for holding individual links, means for moving these maga- 130

zines to bring the links contained therein successively to a common point, and tools at this point operable to remove a link from each magazine and to incorporate these links in a piece of mesh fabric.

35. The combination of a dial having peripheral recesses for holding individual links, a second dial having openings formed through it for holding links, means for rotating the dials with a step-by-step movement, the dials being so disposed that at each period of rest of the movement a recess and an opening are in substantial alignment, and tools operating in the periods of rest of the movement for removing the links from the said opening and recess and for incorporating these links in a piece of fabric.

36. In a machine for making link mesh, the combination of a magazine movable in two directions and arranged to receive links, means at the end of the path of travel of the magazine in one direction for supplying links to it, and means at the end of the path of travel of the magazine in the other direction for removing the links from the magazine and incorporating these links in a piece of fabric.

37. The combination of a rotary magazine adapted to be raised and lowered, means operable for inserting links in the magazine when it is in its lower position, means operable to rotate the magazine when it is in its raised position, and tools operable to withdraw links successively from the magazine when it is in its lowered position and to insert these links in a piece of mesh fabric.

38. The combination of a magazine movable vertically and horizontally, means for inserting links in the magazine at one end of its path of vertical movement, means for removing links from the magazine, and means at the other end of its path of movement for moving the magazine horizontally.

39. The combination of a magazine movable both vertically and horizontally, means for inserting links in the magazine at one end of its path of vertical movement, means spaced therefrom for removing links from the magazine when the latter is at the same end of its path of vertical movement, and means for moving the magazine horizontally when it is at the other end of its path of vertical movement.

40. The combination of a rotary magazine adapted to be raised and lowered, means operable when the magazine is at one end of its vertical movement for rotating it, and means operable to insert links in the magazine when it is at the other end of its path of vertical movement.

41. The combination of a rotary magazine adapted to be raised and lowered, means operable to give the magazine a step-by-step movement of advance when it is at one end of its path of vertical movement, means for

raising and lowering the magazine, the magazine being thus moved between the steps of its rotary advance, means for inserting links in the magazine at one point when the magazine is at the other end of its path of vertical movement and its rotation is arrested, and means spaced from the inserting means and operable simultaneously therewith for delivering links from the magazine.

42. The combination of a shaft, a dial carried thereby, means for raising and lowering the shaft, means operating to rotate the shaft with a step-by-step movement when it is at one end of its path of vertical movement, and means operating when the shaft is at the other end of its path of vertical movement for inserting links in the dial.

43. A forming device for producing links from a strip of blank material comprising the combination of a fixed plunger and a movable plunger disposed on either side of the strip of blank material, these plungers being movable to engage the strip between them and having a shape corresponding to the outline of the link to be removed from the strip, a movable cutter and a cutting block cooperating therewith for cutting the blank along the outline of the part held between the plungers, and means for moving the cutter and cutting block relative to the plungers to force the blank material away from the link held between the plungers and to restore the blank material to its original position, whereby the severed link lies in its original position in the plane of the strip.

44. A forming device for producing links from a strip of blank material comprising the combination of a fixed plunger and a movable plunger resiliently mounted, means for moving the plungers to engage the strip between them, the plungers having a shape corresponding to the outline of the link to be formed, a movable cutter and a resiliently mounted cutting block co-acting therewith, this cutter co-acting with the block to sever the blank along the outline of the link held between the plungers, the plungers lying within and enclosed by the cutter and cutting block, and means for moving the cutter and cutting block and the plungers relatively when these parts are in co-acting relation to cause the blank and the severed link held between the plungers to be separated and to return the co-acting plungers and the co-acting cutter and cutting block to their original positions to restore the excised link to its original position in the plane of the strip.

45. The combination of means for feeding a strip of blank material, guides disposed beyond the feeding means in the direction of movement of the strip through which the strip is advanced, forming means for removing pieces from the strip, a clutch for controlling the operation of the feeding

means, control means for the clutch including a part engaging the strip and operated by its contact therewith when the strip becomes jammed in the guides, and means for preventing the release of the clutch except at a selected stage in the operation of the forming means.

46. The combination of means for feeding a strip of blank material, guides through which the strip is fed, forming means to which the strip is fed operable to act on the strip to change its condition, power driven mechanism for actuating the feeding means and the forming means, a clutch for controlling the action of the feeding and forming means, control means for the clutch having a part in contact with the strip and operable upon the jamming of the strip in the guides to release the clutch, and means for preventing the release of the clutch except at a

selected stage in the operation of the forming means.

47. The combination of feeding rollers for feeding a strip of blank material, guides through which the blank is fed, reciprocating forming means for altering the condition of the strip being fed, driving means for the feeding rollers and the forming means, a clutch for controlling the operation of the feeding rollers and the forming means, control mechanism including a part in contact with the strip for releasing the clutch when the strip becomes jammed in the guides, and means for preventing the release of the clutch by the control means except at a selected stage in the reciprocation of the forming means.

In testimony whereof I affix my signature.

FRED H. LYNDS.
